DESIGN FOR A STEERING WHEEL

William E. Webb, Minneola, Fla.

Application July 18, 1933. Serial No. 48,753

Term of patent 14 years

To all whom it may concern:

Be it known that I, WILLIAM E. WEBB, a citizen of the United States of America, residing at Minneola, in the county of Lake and State of Florida, have invented a new, original, and ornamental Design for a Steering Wheel, of which the following is a specification, reference being had to the accompanying drawing, forming a part thereof.

Figure 1 is a plan view;

Figure 2 is a view in elevation of a steering wheel showing my new design.

I claim:

The ornamental design for a steering wheel, as shown.

WILLIAM E. WEBB.
